UNITED STATES PATENT OFFICE.

JOSEPH A. FRAUENHEIM, OF ZELIENOPLE, PENNSYLVANIA, ASSIGNOR TO AMERICAN FLEXIBLE BOLT COMPANY, OF PITTSBURGH, PENNSYLVANIA, A CORPORATION OF PENNSYLVANIA.

METHOD OF FORMING HOLLOW STAYBOLTS.

1,331,147.

Specification of Letters Patent. Patented Feb. 17, 1920.

Application filed May 31, 1918. Serial No. 237,407.

To all whom it may concern:

Be it known that I, JOSEPH A. FRAUENHEIM, a resident of Zelienople, Butler county, Pennsylvania, have invented a new and useful Improvement in Methods of Forming Hollow Staybolts, of which the following is a full, clear, and exact description, reference being had to the accompanying drawings, forming part of this specification, in which—

Figure 1 is a longitudinal vertical section showing the initial form of the blank and provided with a core-forming filling;

Figs. 2 and 3 are plan views of one end portion of the blank after it has been acted upon by one of the roll passes, the two views being taken at an angle of 90° to each other;

Figs. 4 and 5 are sections taken, respectively, on the lines IV—IV and V—V of Figs. 2 and 3;

Fig. 6 is a longitudinal section of the blank after it has been acted upon by both roll passes;

Fig. 7 is a longitudinal sectional view of a portion of the rolls showing the form of the passes; and

Fig. 8 is a transverse vertical section through the rolls.

My invention has relation to the manufacture of hollow bolts, and more particularly to staybolts in which the intermediate or body portion of the bolt is of smaller diameter than the head portions. The manufacture of such bolts has heretofore been a matter of considerable difficulty. The formation of the central opening through such bolts by boring or drilling is a difficult and expensive operation; and the attempt to form the bolts over a mandrel is also not practicable with small sizes because of the slender character of the mandrel which must be employed.

My invention is designed to overcome these difficulties and to provide a simple, practical and comparatively inexpensive method by which such bolts may be manufactured.

In carrying out my invention, I provide a blank of general cylindrical form and of approximately the same diameter throughout its length, as indicated at 2 in Fig. 1. This blank is provided with a central open-

ing 3, extending longitudinally therethrough. The blank is shorter than the 55 length of the bolt to be formed therefrom, and the internal bore is of a larger diameter than that which it is desired to have in the body portion of the finished bolt, being of such a size that it can be readily bored or 60 drilled, particularly in view of the relatively short length of the blank.

The hollow blank thus formed is provided with a core of some loose or granular heat-resisting material, such as refractory sand, 65 and which may be retained in place by suitable plugs, such as indicated at 4. The intermediate or body-forming portion of the bolt is then subjected to reducing operations which elongate this portion of the blank 70 without changing the diameter of its end or head-forming portions. While these reducing operations may be carried out by means of dies or in any other well known manner, I preferably employ rolls. For 75 this purpose, I may provide a pair of rolls, such as indicated at 5 and 6 in Figs. 7 and 8, each of these rolls having a segmental projection 7, in which may be formed either one or both of the passes 8 and 9, shown in 80 Fig. 7. That is to say, one pair of rolls may be provided with both passes, or separate pairs of rolls may be used for the two passes. The pass 8 is of general elliptical form having the portions 8a, which are 85 adapted to partially shape the part of the blank upon which they act to cylindrical form. The pass 9 is of approximately circular form.

The blank as shown in Fig. 1, after being 90 brought to a suitable heat, is placed between the rolls in the manner shown in Fig. 8, being preferably grasped by a suitable pair of tongs or pincers 10, which are engaged with a suitable stop 11, so as to insure the proper initial position of the blank with respect to the rolls. The roll passes are provided with bevel entrance and exit portions 12, whereby as they act upon the blank, the reduced central portion of the blank will join the un-reduced ends or heads by the tapered frusto-conical portions 13. The pass 8 acts to elongate the body-forming portion of the blank to the desired degree and at the same time partially shape it to cylindrical form. Ow- 100 ing to the elliptical side portions of the pass,

however, the reduced portion of the blank is somewhat elliptical in cross section, and the result of this ellipticity is to form on each of the tapered portions 13 oppositely projecting 5 lips or ridges 14, such as shown in Figs. 2 and 4. These are of considerable importance and are purposely provided, since when the blank is turned 90° and inserted into the second pass 9 these lips or ridges insure a 10 sure initial bite for the rolls. As a result of this, the rolls will begin to act upon and leave the blank at substantially the exact desired points, thereby enabling the reduced portion to be symmetrically and perfectly 15 formed. Without these biting ridges or lips, there is a tendency for the rolls to slip in the second pass, so that their action does not commence and end at exactly the right points. The second blank preferably gives 20 a further slight elongation of the blank, but its main function is to finish the reduced portion of circular cross section.

Owing to the pliable nature of the sand core, the sand will readily flow in the core 25 under the reducing and elongating action of the rolls, so that the internal bore or opening in the blank may be reduced in diameter to substantially the same extent as the reduction in the external diameter of this portion 30 of the blank.

After the blank is taken from the last roll pass, the core-forming material may be removed therefrom and the unreduced end portions threaded in any usual manner.

35 My invention also may be used in reclaiming bolts which are defective by reason of imperfect threads. The end portions of such bolts can be turned down and the resultant article used as an initial blank for the 40 formation of a smaller sized bolt by the described method.

The advantages of my invention will be apparent, since it provides a simple and entirely practicable method by which hollow 45 bolts of this character can be rapidly made at a relatively small cost.

I do not claim herein broadly the method of rolling which is shown and described, as this forms the subject matter of my copending application, Serial No. 237,405 filed May 50 31, 1918.

I claim:

1. The method of forming hollow bolts, which comprises providing a blank having a longitudinal bore therein, said blank being of a length less than that of the bolt to be formed therefrom, filling the bore of the blank with a refractory granular core-forming material, and then subjecting the intermediate body-forming portion only of the blank to a reducing operation to elongate said portion and reduce its diameter relatively to that of the end portions of the blank, substantially as described. 55

2. The method of forming hollow stay bolts, which comprises providing a longitudinally bored blank of cylindrical form and of approximately the same cross section throughout its length, the length of said blank being less than that of the bolt to be formed therefrom, and the blank having a longitudinal bore therein, filling the bore of the blank with a refractory granular core-forming material, and then subjecting the body-forming portion of the blank to a roll-reducing operation to elongate said portion and reduce its diameter relatively to that of the end portions of the blank, substantially as described. 70

3. In the method of forming hollow stay bolts, the steps which comprises providing a longitudinally bored blank of cylindrical form and of substantially the same cross section throughout its length, said blank being of a length greater than that of the bolt to be formed therefrom, filling the bore of the blank with a refractory granular core-forming material, subjecting the intermediate or body-forming portion of the blank only to the action of a roll pass to reduce and elongate said portion of the blank and partially shape it to cylindrical form, then turning the blank approximately 90° and subjecting it to the action of a second roll-pass to shape the reduced portion to cylindrical form, and then threading the unreduced end portions of the blank, substantially as described. 80

In testimony whereof I have hereunto set my hand.

JOSEPH A. FRAUENHEIM.
